DANIEL E. STAIR, OF HUDSON, NEW YORK, AND CHARLES L. McDONALD, OF WASHINGTON, DISTRICT OF COLUMBIA, ASSIGNOR TO GIFFORD-WOOD COMPANY, OF HUDSON, NEW YORK, A CORPORATION OF NEW YORK

COVER INSTALLATION FOR STORAGE BINS

Application filed October 12, 1928. Serial No. 312,098.

This invention relates to covers for storage bins and, among other objects, aims to provide a hatchway cover installation having improved mechanism and control means therefor whereby an operator may cause any selected one of the covers to be automatically opened by a trolley car or carrier to permit dumping of material into the bins.

This application embodies improvements on the copending applications of D. E. Stair filed October 12, 1928, Serial Nos. 312,099 and 312,100.

In the drawings,

Fig. 1 is a plan view showing an illustrative installation of covers applied to a series of storage bins, one of the covers being shown in open position;

Fig. 2 is a vertical, longitudinal, sectional view through one of the bins drawn on an enlarged scale and showing a portion of a trolley car in section;

Fig. 3 is a fragmentary, longitudinal, sectional view through the cover mechanism and drawn on a still larger scale; and

Fig. 4 is a fragmentary plan view of the operating lever and solenoid armature.

Referring particularly to the drawings, the improvements are shown as being applied to a storage bin installation similar to those shown and described in said Stair applications. Such installations include generally a series of storage bins 9 having hatchways in the roof 10, said hatchways each being normally closed by a movable cover 11 arranged to be opened when a load of material is to be dumped within a bin from a trolley car or conveyor 12 mounted on rails above the bins. The covers are here shown as being mounted to move up inclined tracks 13 to open position and are adapted to close by gravity.

In order that any selected one of the covers may be automatically opened by the trolley car, movable abutments 14 are shown on the cover and are adapted to be engaged by a fixed abutment 15 or other part of the car or conveyor. Herein, the movable abutments are normally out of the plane of travel of the fixed abutment on the car, but are constructed and arranged to be moved into position to be engaged by said fixed abutment.

In the present example, each of the movable abutments is in the form of an arm 16 pivoted as at 17 to a stationary bracket 18 on the cover 11, said arm being connected to be actuated by a movable plunger 19 (Figs. 2 and 3). The arm is provided with an offset counterweight 20 which normally rests on the top of the cover and holds the arm below the plane of travel of the fixed abutment 15 on the car, as indicated in dotted lines in Fig. 3. When a cover is to be opened by the car, the arm 16 is swung upwardly into substantially vertical position and strikes against the upstanding leg 21 of the bracket 18, the upper end being in position to be engaged by the abutment 15 to open the cover.

The mechanism for raising the arm 16 to operative position is shown as comprising a crank arm 22 which is secured thereto and has a pin and slot connection with the upper end 70 of a plunger 23 slidably mounted in a sleeve 24 extending through the cover. The lower end of the plunger 23 has a pin and slot connection with one end of a lever 25 which is pivoted intermediate its ends at 26 on the 75 under side of the cover, the other free end 27 of the lever extending slightly beyond the lower end of the cover and passing beneath the roof through an opening in one of the roof beams. The combined weight of the 80 free end 27 of the lever 25 and of the counterweight 20 is such as to cause the operating mechanism, thus far described, to assume the positions shown in Fig. 2 and in dotted lines in Fig. 3, the arm 16 being swung down. 85 When the free end 27 is raised, the parts will be in operative position, as shown in full lines in Fig. 3.

In order to raise the free end 27 it is slotted (Figs. 3 and 4) to provide a cross bar 28, 90 which coacts with cam portions formed on the plunger 19. The cam portions 29 and 30 are inclined upwardly toward each other and are connected at their upper ends by a straight portion 31 on which the cross bar 95 rests when raised. When the plunger is in normal position (Fig. 2), the cross bar 28 rests on the main body of the plunger behind the rear inclined portion 29 which then extends upwardly through the slot in the end 100

27 of the lever. When the plunger is moved away from the cover, or to the left, as viewed in the drawings, the cross bar 28 will ride up the inclined portion 29 and come to rest on the straight portion 31, causing the arm 16 to rise to operative position, as shown in full lines in Fig. 3.

The plunger is adapted to be actuated by a solenoid 32, preferably constituting the armature of the solenoid, as shown, although the plunger may be separate from and connected to the armature. Whatever the arrangement, the plunger is to be automatically returned to normal position when the solenoid circuit is broken. If desired, a roller 33 may be employed to support the plunger.

In order to manually operate the plunger in case of necessity, a cable 34 may be connected to the plunger and passed over a pulley 35 on the outside of the bin to the ground, where it may be grasped by an attendant on the ground and pulled to operate the mechanism.

To cause the car to stop when the cover is open, a stop switch 36 which is mounted on the car, is connected in the motor circuit of the car and has a depending plunger 37 adapted to be engaged by the upper end of the arm 16, as the cover nears the upper end of its track. When the cover has reached its open position, the arm 16 will have raised the plunger far enough to open the switch to break the motor circuit.

It is to be understood that there is to be a separate solenoid and associated mechanism for each bin cover, the solenoids being connected by suitable wiring 38 to a source of current 39 and to a series of push button switches 40 or the like located at any desired point.

In bin installations of this type, the tram car is adapted to be controlled from an operator's house on the ground (not shown) and the switches for controlling the solenoids may be located in the same house, so that the cover of any desired bin may be selected to be opened by merely closing a switch. Also, the cables 34 may be extended to the operator's house, if desired.

If it is desired to use the same bin for a considerable length of time, the switch, controlling the solenoid of the particular bin, is left closed for that period, causing the plunger 19 to remain in its retracted position or that shown in full lines in Fig. 3. Whenever the car returns for another load and the cover gravitates to closed position, the cross arm 28 will strike and ride up the front inclined portion 30 of the plunger and reset the arm 16 in operative position.

From the foregoing description, it will be apparent that the improved control means and cover operating mechanism are utilized to avoid the necessity of having an operator on the car or conveyor. Moreover, the arrangement permits a single attendant on the

ground, who may have a number of different duties, to control the operation of a bin conveyor or a series of conveyors. If one bin is selected to be filled, the appropriate switch may be operated to preset the cover mechanism and no further attention to it will be required until another bin is selected. Further, the mechanism is relatively simple and can easily be installed on old storage bins.

Obviously the present invention is not restricted to the particular embodiment thereof herein shown and described. Moreover, it is not indispensable that all the features of the invention be used conjointly, since they may be employed advantageously in various combinations and sub-combinations.

What is claimed is:—

1. In combination with a series of storage bins, movable covers over the bins; a tramway over the bins; a tram car on the tramway; and movable means on the covers selectively engageable with the tram car whereby the tram car automatically opens any selected one of said covers.

2. In combination with a series of storage bins, movable covers over the bins; a tramway over the bins; a tram car on the tramway; movable means on the covers selectively engageable with the tram car whereby the tram car automatically opens any selected one of said covers; and remote control means for effecting the selective engagement.

3. In combination with a series of storage bins having movable covers and a trolley car adapted to traverse the series; an abutment on the car; a movable abutment on each cover normally out of the plane of travel of the abutment on the car; means for moving the movable abutment into said plane to be engaged by the abutment on the car; and remote control means for said abutment moving means.

4. In combination with a series of storage bins, movable covers over the bins; a tramway over the bins; a tram car on the tramway; an operator-controlled, electrically operated mechanism mounted on and adjacent to each cover to cause the tram car to selectively and automatically open any one of the covers.

5. In combination with a series of storage bins, movable covers over the bins; a tramway over the bins; a tram car on the tramway; electrically operated mechanism to cause the tram car to automatically open any one of the covers; and remote switch means to control said electrical mechanism and to govern the selection of the cover to be opened.

6. In combination with a series of storage bins, movable covers over the bins; a tramway over the bins; a tram car on the tramway; means on each cover movable into tram car-engaging position; and a solenoid connected and arranged to actuate said means.

7. In combination with a series of storage

bins, movable covers over the bins; a tramway over the bins; a tram car on the tramway; means on each cover movable into tram car-engaging position; and a solenoid connected and arranged to actuate said means; and means to reset said movable means when the cover is re-closed.

8. In combination with a series of storage bins, movable covers over the bins; a tramway over the bins; a tram car on the tramway; a pivoted arm on each cover adapted to be moved into tram car-engaging position; and means for moving said arm.

9. In combination with a series of storage bins, movable covers over the bins; a tramway over the bins; a tram car on the tramway; a pivoted arm on each cover adapted to be moved into tram car engaging position; and solenoid operated mechanism for moving said arm.

10. In combination with a series of storage bins movable covers over the bins; means adapted to automatically close said covers; a movable carrier above said bins; means on the covers selectively engageable with the carrier to cause the carrier to open any one of the covers; and means to reset said means on the cover in carrier-engageable position when the cover returns to closed position.

11. In combination with a series of storage bins having a roof thereon and a hatchway therein for each bin, a movable cover for each hatchway; means adopted to automatically close said covers; a movable carrier on the bins; a slideable plunger associated with each cover and mounted on the roof; a pivoted arm on each cover adapted to be moved in carrier engaging position; a pivoted link connected to the arm and operable by the plunger to move the arm into position; and solenoid means for actuating the plunger.

12. In combination with a movable cover of the character described, a pivoted arm on the cover adapted to be selectively engaged by a movable carrier to open the cover; a pivoted lever on the opposite side of the cover having one end connected to operate the arm; and remote controlled means including a plunger engageable with the lever and arranged to move and hold the arm in its operative position.

13. In combination with a movable cover of the character described, a pivoted arm on the cover adapted to be selectively engaged by a movable carrier to open the cover; a pivoted lever on the opposite side of the cover having one end connected to operate the arm; and a solenoid having an armature slidably engaging the free end of the lever effective to move and hold the pivoted arm in its operative position.

14. In a bin installation having a series of movable hatchway covers and a material conveyor to discharge into the bins, a movable arm on each cover adapted to be selec-

tively engaged by the carrier; solenoids having armatures connected to actuate the respective arms; and pulling elements connected to said armatures whereby the arms may be actuated manually.

15. In combination, a series of bins, movable covers for the several bins; a material conveyor to move over and discharge into the bins; a movable arm on each cover adapted to be selectively engaged by the conveyor; and co-operating electrically and manually actuated means for moving said arms; said means being located partly on the bins and partly on the covers.

16. In combination with a storage bin, a roof on the bin having a hatchway therein; a movable cover for the hatchway; a carrier movable over the bin; an abutment fixed on the carrier; a pivoted arm on the top of the cover adapted to be moved in position to be engaged by the abutment; a crank arm connected to the pivoted arm; a plunger having a pin and slot connection at its upper end with the crank arm and slideable through the cover; a lever pivoted intermediate its ends beneath the cover and having a pin and slot connection at one end with the lower end of the plunger; operator-controlled means for actuating the free end of the lever to effect engagement between the pivoted arm and the abutment, so that the carrier may open the hatchway by pushing the cover; and means to close the cover automatically when the carrier moves away.

17. In combination with a storage bin, a roof on the bin having a hatchway therein; a movable cover for the hatchway; a carrier movable over the bin; an abutment fixed on the carrier; a pivoted arm on the top of the cover adapted to be moved in position to be engaged by the abutment; a crank arm connected to each pivoted arm; a plunger having a pin and slot connection at its upper end with the crank arm and slideable through the cover; a lever pivoted intermediate its ends beneath the cover and having a pin and slot connection at one end with the lower end of the plunger; the other end of the lever extending beneath the roof and having a cross bar; an operator-controlled solenoid having an armature mounted beneath the roof adjacent to the cross bar of the lever; a slideable plunger connected to the armature and having cam portions co-operating with the cross bar of the lever to raise the same, thereby to raise the pivoted arm so that it is engaged by the abutment, so that the cover is opened by the carrier.

18. In combination with a storage bin, a roof on the bin having a hatchway; an inclined track for the hatchway; a hatchway cover adapted to be moved to the upper end of the track to open the hatchway and adapted to gravitate to close the same; a carrier movable over the bin; an abutment fixed on

- the carrier; an arm pivotally mounted on the top of the cover; a counterweight on the arm to hold the arm normally below the plane of travel of the lower end of the abutment; a crank arm on the pivoted arm; a lever pivotally mounted intermediate its ends on the underside of the cover; means connecting the one end of the lever to the end of the crank arm; the other end of the lever extending beyond the lower end of the cover and beneath the roof; a plunger slidably mounted beneath the roof and co-operating with the free end of the lever to raise the pivoted arm so that it will be engaged by the abutment; means fixed on the cover adjacent the pivoted arm and forming a stop for said arm to prevent it from being swung beyond the upright position and to transmit the thrust from the moving abutment to the cover; and operator-controlled means to move the plunger.
19. In combination with a storage bin, a roof on the bin having a hatchway; an inclined trackway for the hatchway; a cover on the track adapted to move to the upper end of the track to open the hatchway and to gravitate to close the same; a carrier movable over the bin; an abutment fixed on the carrier; an arm pivotally mounted on the top of the cover intermediate the ends thereof; a counterweight on the pivoted arm normally to hold the arm below the plane of travel of the abutment; a crank arm on the pivoted arm; a slideable plunger beneath the roof adjacent the lower end of the trackway; cam portions on the plunger; means connected to the crank arm and operable by the cam portions on the plunger to project the pivoted arm in the plane of the abutment; and operator-controlled means to actuate the plunger.
20. In combination with a storage bin, a roof on the bin having a hatchway; an inclined trackway for the hatchway; a cover on the track adapted to move to the upper end of the track to open the hatchway and to gravitate to close the same; a carrier movable over the bin; a fixed abutment on the carrier; an arm pivotally mounted on the top of the cover intermediate the ends thereof; a counterweight on the arm adapted normally to hold the arm below the plane of travel of the abutment; a crank arm on the pivoted arm; a slideable plunger beneath the roof adjacent the lower end of the trackway; cam portions on the plunger; means connected to the crank arm and operable by the cam portions on the plunger to swing the pivoted arm upwardly into the plane of the abutment; means to limit the upward swinging movement of the arm; solenoid means to actuate the plunger; and a pulling element connected to the plunger whereby the plunger may be actuated manually.
21. In combination with a storage bin, a roof on the bin having a hatchway; an inclined trackway for the hatchway; a cover on the track adapted to move to the upper end of the track to open the hatchway and to gravitate to close the same; a carrier movable over the bin; an abutment fixed on the carrier; an arm pivotally mounted on the top of the cover intermediate the ends thereof; a counterweight on the arm adapted normally to hold the arm below the plane of travel of the abutment; a crank arm on the pivoted arm; a lever pivoted beneath the cover; means connecting the lever to the crank arm; said pivoted arm being raised so as to be engaged by the abutment when the lever is moved on its pivot; and operator-controlled, solenoid-actuated means for moving said lever.
22. In combination with a storage bin, a roof on the bin having a hatchway; an inclined trackway adjacent the hatchway; a cover adapted to move to the upper end of the track to open the hatchway and to gravitate to close the same; a carrier movable over the bin; an abutment fixed on the carrier; an arm pivotally mounted on the top of the cover intermediate the ends thereof; a counterweight on the arm to normally hold the arm below the plane of travel of the abutment; a crank arm on the pivoted arm; a lever pivoted beneath the cover; means connecting the lever to the crank arm, said pivoted arm being raised to position to be engaged by the abutment when the lever is moved on its pivot; a plunger slidably mounted beneath the roof and having cam portions adapted to engage with and move the lever on its pivot; and remote control means for moving the plunger.
23. In combination with a series of storage bins each having an automatically closing hatchway cover mounted to roll up an inclined trackway to open position; a trolley car guided to travel horizontally over the bins in the direction of opening movement of said covers; an abutment fixed on the car; a pivoted arm on each cover normally held below the plane of travel of the abutment; operator-controlled solenoid-actuated means for swinging the arm upright into the plane of travel of the fixed abutment; an electric switch on the car and having a depending plunger arranged in the path of the vertical movement of the arm when the cover is being opened by the car, whereby to break the trolley circuit and bring the car to a stop when it has reached the unloading position over the open hatchway.
- In testimony, that we claim the foregoing as our own, we have hereto affixed our signatures.
- DANIEL E. STAIR.
CHARLES L. McDONALD.
